SOLVENT EXTRACTION OF VITAMIN A FROM FISH LIVER OIL

Filed Jan. 29, 1947

UNITED STATES PATENT OFFICE

2,573,897

SOLVENT EXTRACTION OF VITAMIN A
FROM FISH LIVER OIL

Stephen E. Freeman, Pittsburgh, Pa., and Stewart W. Gloyer, Milwaukee, Wis., assignors to Pittsburgh Plate Glass Company, Allegheny County, Pa., a corporation of Pennsylvania

Application January 29, 1947, Serial No. 725,108

9 Claims. (Cl. 167—81)

1

The present invention relates to separation of concentrates of oil soluble vitamins such as vitamins A and D (if D is present) from certain vitamin bearing oils and has particular relation to the separation of such concentrates by means of organic polar solvents.

One object of the invention is to provide a simple and inexpensive process of obtaining concentrates of vitamin A suitable for use in capsules and pills from vitamin A containing oils which normally are of too low concentration satisfactorily to be so employed.

A second object is to provide a process of obtaining vitamin A concentrates which is simple and relatively inexpensive to operate.

A third object is so to treat a glyceride oil containing vitamins soluble therein as to effect separation of the oil into a plurality of fractions one of which is greatly enriched in vitamins.

A fourth object is to provide a process of the foregoing type, the application of which does not result in substantial loss of the vitamins in the oil.

A fifth object is to provide a process of obtaining concentrates of vitamins from glyceride oils containing vitamins in low or moderate concentration with selective polar solvents which can with most solvents be operated at temperatures near or not much below normal room temperature.

A sixth object is to provide the process of obtaining concentrates of oil soluble vitamins by solvent extraction which involves dissolving in the solvent a minimum amount of the fatty glycerides of the oil and a maximum amount of the vitamins contained in the oil.

These and other objects of the invention will be apparent from consideration of the following specification and the appended claims.

It has heretofore been proposed to obtain concentrates of oil soluble vitamins such as vitamins A and D from vitamin bearing glyceride oils such as fish liver oils by various methods. Complicated and expensive chemical procedures have been proposed for the purpose. For example, it has been proposed to saponify the glycerides in the oil with an alkali and then to extract the vitamins from the soaps by means of hydrocarbons. The technique involved was complicated and expensive. It has also been proposed molecularly to distill concentrates of vitamin A from the oils. The methods of distillation employed for the purpose are highly technical and require the application of very high vacua. The technique is expensive, especially where large volumes of the more plentiful fish liver oils of low or moderate concentration constitute the original source of vitamins and is likely to result in some degree to degradation of the vitamins. In cer-

2

tain patents such as U. S. Patents 2,380,418, 2,380,414, 2,380,410, and 2,347,460 it has been proposed to obtain concentrates of vitamins from vitamin bearing oils by first heating a mixture of oil and a solvent such as isopropyl alcohol in order to dissolve the oil in the solvent and then cooling the solution to a temperature of 0 to -70° C. in order to effect separation of a large portion of the glycerides from the solvent. The vitamins were thus substantially concentrated in the solvent. These patents disclose processes which apparently require batchwise operation. This is true because in some instances the oil is completely dissolved in the solvent. Obviously countercurrent flow of the components in solution is impossible. In other instances, the oil containing vitamins and the solvent are admixed under conditions of reflux for the solvent. Countercurrent flow of a refluxing solvent and oil would be highly impractical if not impossible. Such system would also necessitate use of solvents having very low solvency for the oil. Obviously, the techniques involved were slow and expensive.

In certain patents such as U. S. 2,200,390 and 2,200,391 procedures are disclosed for the fractionation of certain glyceride oils to obtain concentrates of the more unsaturated components by liquid phase extraction with organic polar solvents. The procedures as outlined in the patents are not applied to the concentration of vitamins.

In U. S. Patent 2,090,739 to Tischer, it is proposed to wash a vitamin bearing oil such as cod liver oil or the like with a polar solvent such as furfural in order to remove odor, color, and taste constituents from the oil without substantially reducing the vitamin concentration of the oil remaining as a raffinate.

The present invention contemplates a process whereby oils containing vitamins such as vitamins A and D are obtained in high concentration from vitamin bearing oils even of low or moderate vitamin concentration by a simple process of liquid phase countercurrent extraction with organic polar solvents such as are disclosed in the above mentioned Patent 2,200,391 to obtain a major portion of the vitamins in a minor extract portion of the total oil treated.

For a better understanding of the invention reference may now be had to the accompanying drawing in which the single figure diagrammatically illustrates a suitable embodiment of apparatus for obtaining concentrates of vitamins by continuous liquid phase countercurrent extraction of oils such as fish liver oils. In the drawings, like numerals refer to like parts throughout.

In the practice of the invention any one of a number of selective polar solvents may be employed to obtain a fraction of glyceride oils which

are greatly enriched in vitamin A simultaneously, vitamin D, if present, will be similarly concentrated. In general, the solvents will be organic polar solvents such as those disclosed in Patent 2,200,391 to Stephen E. Freeman. In the patented process the solvents are employed to separate natural glyceride oils such as linseed oil, soy bean oil, or the like, non-vitamin bearing oils, into fractions upon the basis of unsaturation of the glyceride molecule. In the patented process as well as in the present process, it is required that the solvents, in addition to being polar, be but partially miscible with the oil at the temperature of operation so that the oil-solvent system can be separated into two liquid phases from which the solvent can be evaporated. The ultimate or final extract phase will comprise most of the solvent and a minor proportion of the oil in which vitamins A and D are highly concentrated. The final raffinate oil constituting most of the 15 glyceride and especially most of the more saturated glyceride will be correspondingly impover-

ished in vitamins and will contain in solution a minor amount of the solvent employed.

Appropriate polar solvents can usually be selected by a simple test involving shaking up a templated polar solvent with a small amount of the oil to be extracted in a test tube or a separatory funnel or other suitable laboratory apparatus and observing if the oil and the solvent at a definite constant temperature tend to separate into two liquid phases so that the extract or solvent phase will contain 2 to 25% of the original oil. Concentration of vitamins in the extracted oil can easily be determined by well known chemical, physical or biological tests.

The following table illustrates the application of such test to a large number of polar solvents. These tests were conducted upon dogfish liver oil containing about 10,000 units of vitamin A per gram. The same test obviously could be conducted upon other vitamin bearing oil such as cod liver oil, soupfin shark liver oil, halibut liver oil and others:

Solvent	Per Cent Yield of Ext.	Solv. Ratio	Temp., °C.	Units Vit. A/gram		Vitamin Diff.
				Extract	Raff.	
Hydroxyl:						
Methyl alcohol	7.0	10:1	39	18,180	9,520	8,660
Ethyl alcohol, 95%	16.6	8:1	61	14,800	8,700	6,100

Binary Solvents:						
1 part naphtha	10.0	9:1	25	18,180	7,410	10,770
1 part naphtha						
6 parts monomethyl ether of ethylene glycol	11.5	6:1	41.5	20,000	7,140	12,860

The following constitutes a partial list of some of the more favored polar solvents that can be employed in the operation of the processes herein described:

Methyl lactate
Methyl carbitol
Methyl acetoacetate
Acetonitrile
Methyl alcohol
Monomethyl ether of ethylene glycol
Furfuryl alcohol
Acetic acid
Glycol diacetate
Acetonyl acetone
Nitromethane
Dimethyl formamide
Furfural

It will be apparent that in each instance where the oils and the polar solvent to be tested were but partially miscible, there was some degree of concentration of the vitamins as determined by appropriate tests for vitamins in the extraction phase, that is the solvent predominant phase. In some instances the concentration was very pronounced indicating that these solvents would be especially suitable for use as solvents in a counter-current extraction in accordance with commercially feasible methods hereinafter outlined. Counter-current extraction is, of course, susceptible of giving much higher degrees of vitamin concentration than the batch extractions.

Suitable apparatus for commercial operations as diagrammatically illustrated in the drawings includes a column 10 which constitutes a vertically elongated extraction zone and which may be appropriately packed with rings, saddles, baffles or the like. The column preferably is fairly long, e. g. 50 ft. or more in the extraction zone and it may be provided with suitable means for maintaining a temperature gradient between the top and bottom. Such device may comprise a number of jackets, e. g. upper jacket 10a and lower jacket 10b having inlets 10c and outlets 10d through which a suitable heating transfer medium may be circulated. Other heating or cooling device such as coils in the column for circulating a transfer medium, electrical resistance heaters, or the like may also be employed. The mixture from various positions in the column may also be withdrawn, passed through a heat exchanger 10f to either cool or heat the mixture and finally be repumped back into the column at any desired position. Oil constituting a source of vitamin A or A and D, is brought in as indicated at 11 from a storage container 11a to a zone approximately at the middle of the column. An appropriate organic polar solvent such as furfural is introduced from container 12 through line 12a into column 10 a short distance below the top of the column in such manner as to provide a zone 13 in which the separation of the liquid raffinate from the solvent can take place.

The raffinate consisting mainly of a fraction of the original oil impoverished in vitamin A is drawn off through a line 14 at the top of the column. It may be delivered to an appropriate still 15 where it is stripped of dissolved solvent. The vapors of solvent are then recovered in a condenser 16 and the liquid solvent is recycled to storage 12 through a line 16a. Certain alternative modes of treating the oil will subsequently be described.

The extract oil contained in the solvent will

contain in solution most of the vitamins A and D (if D is present) and is taken off near the bottom of the column through line 17. It likewise may be stripped of solvent in a still such as 18 and the solvent vapors may be passed through conduit 19 to condenser 21 for recovery. The liquid solvent is drawn off through lines 22 and 16a to storage tank 12 where it is combined with that from condenser 16.

10 The yield of extract product oil from column 10 taken in line 20, based upon the original feed oil, will depend upon the mode of operation of the system as hereinafter more completely described. It may constitute the final extract product of the system in which case it will constitute about 2 to 25% of the original oil in which most or a large proportion of the vitamin A preferably is concentrated. Some of this extract oil, e. g. 10 to 95%, stripped, or at least partially stripped 20 of solvent may be recycled or refluxed through a conduit 24 to a zone in column 10, a short distance above the bottom thereof. Usually the extract phase so recycled will contain no more than 50% solvent. The proportion may be much lower. Assuming that the selective solvent is furfural which is of a density of 1.1598, while fish liver oil is about .925, evaporation of solvent reduces the density of the resultant solution so that the reflux will tend to rise through the 30 downwardly flowing extract solution. The reflux may even be completely stripped. This reflux increases the vitamin content in the lower zones of the column and thus produces an enriched extract product. The refluxing action may be termed "rectification." In order to control the ratio of reflux to extract product taken, suitable control devices are provided. The simplest form of such device of course would involve valves such as valves 27 and 28 in lines 20 and 24. If valve 28 is closed there will be no reflux and the extract oil will pass to storage in a container 29; or if certain alternative procedures are followed, as hereinafter will be described, it may be passed on through line 20a controlled by valve 20b to a column 31, which constitutes a second vertically elongated extraction zone, for further extraction.

The column 31 can in the alternative be:

50 (a) Eliminated from the system, in which instance it is possible to obtain adequate yields of extract containing a concentrate of vitamin A by use of (1) reflux through line 24 and, or (2) by maintaining the upper part of the column at a higher temperature than the lower part, such effect being attained by circulating heat transfer media in jackets 10a and 10b or by feeding in solvent at the top of the column at a higher temperature than the feed oil or by other methods, such as by circulating column solutions through external heat exchangers, such as the heat exchanger 10f where the liquids are cooled or heated as may be required.

65 (b) A small extract (2 to 25%) of high vitamin concentration can be taken and the raffinate can be re-extracted in column 31. The second extract can be recovered as a third product or it may be returned to the original feed. The second raffinate is a final product of use in stock feed or other purposes.

70 (c) A moderate or large (e. g. 25 to 75%) extract can be taken from column 10 and a correspondingly reduced raffinate taken preferably as a final relatively low vitamin potency product.

The extract of a higher vitamin content than the

original oil can be re-extracted in column 31 and the second extract taken as the highest vitamin concentrate of the system while the second raffinate is recovered as a third product or may be recycled to the feed of column 10.

Assuming that one of the alternative methods b or c is employed, solvent from tank 12 is introduced into the column 31 by lines 31a at a point slightly below the top of the latter. The raffinate of the column is taken off at the top through line 32 and passes into still 33 where solvent medium may be stripped off and passed on to condenser 34 for recycling through line 34a to solvent storage. Dependent upon the mode of operation of the system, solvent free raffinate may pass through line 35 to storage in container 36 or, alternatively, it may be returned through a line 35a having a control valve 35b to the oil supply container 11a. It will be apparent that since the raffinate is usually low in dissolved solvent, it may not be necessary to strip it before recycling it as feed oil to column 10. The invention, therefore, contemplates recycling of raffinate from column 31 with or without stripping in still 33, to column 10 directly through line 11 in conjunction with original feed oil.

Extract from column 31 which may be a final vitamin concentrate or a product suitable for recycling and mixture with the original feed oil to column 10 dependent upon whether alternative b or c is employed, passes off through line 31 to still 38 where the solvent is stripped and delivered through line 39 to condenser 40 and is finally returned to storage through lines 41 and 34a. The extract oil is drawn off through line 42. It may go in its entirety to storage 43 or a part may pass through a line 44 to provide reflux to lower zones of column 31. This reflux in part controls the vitamin content of the extract of column 31. The ratio of reflux may be controlled by valves 45 and 46 which can be opened or closed to determine the ratio of reflux of the extract.

Instead of passing the extract oil of column 31 to storage or to reflux in the column, all or a part of it can be sent through line 47 to the feed storage container 11a for return to column 10. Reflux through line 44 is again permissible. Valves 48 and 49 in lines 42 and 47 then determine the course of the extract oil from the column 31.

In the specific examples appended hereto are illustrated conditions of operation of the columns 10 and 31 for use with dogfish oil containing about 10,000 to 20,000 units of vitamin A per gram and with furfural as a polar solvent. Example 1 illustrates the operation of the system in accordance with alternative b in which a small extract fraction of high vitamin content is taken from column 10, this constituting the final vitamin concentration as obtained from the system. The extract from column 31 is in this instance employed as a part of the feed oil and the raffinate from column 31 is employed as the final low vitamin product of the system.

EXAMPLE 1

Oil used.—Dogfish liver oil containing 10,000 units of vitamin A per gram.

Conditions of operating column 10

Solvent ratio, 8:1 based on oil feed rate
Solvent used, anhydrous furfural
Oil reflux, none
Temperature, 58-60° F.

Products	Per Cent Yield	Taken from Line	Units Vit. A/gm.
Extract.....	17.4	20	24,800
Raffinate.....	82.6	28a	5,800

Conditions of operating column 31

Oil used, raffinate oil from column 10, line 29a
Solvent used, anhydrous furfural
Solvent ratio, 10:1 based on raffinate oil feed rate, line 29b
Oil reflux, none
Temperature, 96-100° F.

It is to be observed that in this example the second column (31) is operated at a substantially higher temperature than the first (10), thus to obtain the desired vitamin concentrate from the first column. The reflux of Example 3 or the temperature gradient of Example 4 could be applied in this example.

Products	Per Cent Yield	Taken from Line	Units Vit. A/gm.
Extract.....	40.3	42	12,360
Raffinate.....	59.7	35	2,100

In the above series of extractions three final products are produced, the yields and potencies of these being given in the following table:

Products	Per Cent Yield	Taken from Line	Units Vit. A/gm.
Extract.....	17.4	20	24,800
2nd Extract.....	33.2	42	12,360
2nd Raffinate.....	49.4	35	2,100
Original Oil.....			10,000

If it is desired the second extract may be blended with the original feed oil and be re-extracted in column 10.

In Example 2 the system is operated in accordance with alternative c as above outlined, the raffinate from column 10 constituting a final low vitamin product, the extract of column 31 constituting the high vitamin product and the raffinate of column 31 being returned to the feed oil of column 10. The conditions of operations 50 were as follows:

EXAMPLE 2

Oil used.—Dogfish liver oil containing 10,000 units of vitamin A per gram.

Conditions of operating column 10

Solvent ratio, 10:1 based on oil feed rate
Solvent used, anhydrous furfural
Oil reflux, none
Temperature, 93° F.

Products	Per Cent Yield	Taken from Line	Units Vit. A/gm.
Extract.....	50.7	20	22,000
Raffinate.....	49.3	28a	2,260

Conditions of operating column 31

Oil used.—Extract oil from column 10, lines 20 and 20a.
Solvent used, anhydrous furfural
Solvent ratio, 8:1 based on extract oil feed rate, line 29b
Oil reflux, none
Temperature, 67° F.

It is to be observed that in this example the second column (31) is operated at a lower temperature than the first (10), thus to obtain the lower ratio of extract as the high vitamin concentrate from the latter.

Products	Per Cent Yield	Line	Units Vit. A/gm.
Extract.....	28.2	42	34,000
Raffinate.....	71.8	35	7,460

In the extractions in this example three products are produced, the yields and potencies of these being given in the following table:

Products	Per Cent Yield	Line	Units Vit. A/gm.
1st Raffinate.....	49.3	29a	2,260
2nd Raffinate.....	36.4	35	7,460
2nd Extract.....	14.3	42	34,000

The second raffinate may be blended with the original feed oil.

In the third example column 31 was cut out of the system and column 10 was operated with a reflux to obtain in the single column a high vitamin extract and a low vitamin raffinate. The conditions in the system were as follows:

EXAMPLE 3

Oil used.—Dogfish liver oil containing 10,000 units of vitamin A per gram.

Conditions of operating column 10

Solvent used, anhydrous furfural
Solvent ratio, 20:1 based on oil feed rate
Oil reflux, 0.5:1 based on oil feed rate
Temperature, 70-71° F.

Products	Per Cent Yield	Line	Units Vit. A/gm.
Extract.....	28.8	20	33,000
Raffinate.....	71.2	29a	1,700

In a further example illustrating the practice of the invention relatively high concentrations of vitamins in the extract oil obtained from column 10 was accomplished by maintainance of a temperature gradient between the top and bottom of the column. In this process the temperature gradient may be attained by use of heating or cooling elements at appropriate points in the column, for example by means of jackets 10a and 10b or by use of the heat exchanger 10f, which may be supplied with an appropriate heated liquid, or by the employment of solvent at a temperature above that of the feed oil. In the example the second column was not employed. It is obvious that a temperature gradient may also be maintained where a second column is employed to re-extract either the raffinate or the extract from column 10. The conditions employed where a temperature gradient was maintained and furfural was employed as the polar solvent are illustrated by the following examples:

EXAMPLE 4

Oil used.—Dogfish liver oil containing 17,400 units of vitamin A per gram.

Conditions of operating column 10

Solvent used, naphtha saturated furfural
Solvent ratio, 8.3:1 based on oil feed rate
Oil reflux, none
5 Naphtha reflux, 0.13:1 based on oil feed rate
Column temperatures:

Top, 148° F.
Bottom, 48° F.

10	Products	Per Cent Yield	Units Vitamin A/gm.
Extract.....	14.2	71,500	
Raffinate.....	85.8	8,060	

15 The raffinate in this example could be used as feed oil in Examples 1, 2 or 3 or could be admixed with fresh oil therein and re-extracted to recover a second extract of improved vitamin A concentration. Such second extraction may or may not be preceded by stripping of the solvent in the raffinate. In Example 4 it will be apparent that the temperature of the system at the top of the column could have been somewhat higher than given in the example though, of course, it should not be so high as to induce excessive solution of the particular oil being treated. Similarly, the temperature at the bottom of the column may be reduced below the value given in the example but again it should not be so low as to excessively reduce the fraction being taken off. Preferably, the extract will constitute 2 to 25% of the feed oil.

20 35 The extract solutions of oil as obtained in the foregoing examples may be further extracted with a paraffinic hydrocarbon, e. g. a naphtha approximating a heptane to decane in average molecular weight. By such treatment the glycerides and 40 vitamins are washed from the polar solvent, leaving most of the free fatty acids, coloring matter, odor, and taste constituents concentrated in latter solvent. In such process, the naphtha may be in variable proportion, but 14 to 1 based on oil 45 feed rate is satisfactory. The extraction may be effected counter-currently in a column at a temperature of about 70 to 75° F. These values are quite appropriate for dogfish liver oil. Some degree of variation for other oils to compensate 50 for differences in solubility of other vitaminiferous oils may be desirable.

55 In the specific Examples 1 to 4 inclusive the oil treated was dogfish liver oil containing vitamin A in the proportions indicated. It will be obvious that various other vitaminiferous oils notably of the fish liver type such as tuna fish oil, halibut liver, shark liver oil or other oil may be substituted. With such substitutions some variation in the temperature values given may be 60 desirable since each of these oils has its own solubility characteristics.

65 Similarly, it will be apparent that various other polar solvents such as those included in Table A may be substituted for the furfural of Examples 1 to 4 inclusive, the solvents being employed to extract dogfish liver oil or any of the other oils herein enumerated, the temperatures of solubility of the oils found in any of the selective solvents being determined by the methods herein 70 discussed. The ratio of solvent to oil may be approximately those values given for purpose of illustration in Table A and the temperatures may also be the same or similar to those tabulated. Though, as in the case of furfural, wide variation of ratios of solvent, for example in the range 75

of 3 to 30 parts of solvent by volume for each part of vitamin bearing oil is contemplated. Similarly, the temperatures of extraction are susceptible of considerable variation, though the temperature in the zone from which the final extract is taken should not be so high as to take out more than about 25% or less than about 2% of the oil upon the basis of the original feed oil. A range of 10 to 80° C. covers nearly all contingencies.

The vitamin depleted raffinate oil from the extraction can be used as a source of vitamin A, e. g. in chicken or cattle feed.

The products as obtained by the foregoing procedures will be of relatively high vitamin A concentration as compared with the oils from which they were derived. This concentration will vary somewhat dependent upon the vitamin A concentration of the original oil.

These products in most instances are sufficiently high in concentration for their use as vitamin A concentrates such as are employed in filling capsules. However, if desired it is permissible further to treat the oil in order to obtain still higher concentrations of vitamins. For example, the extracted oil containing a very high concentration of vitamins may be suitably saponified with alkalis such as sodium hydroxide, potassium hydroxide or the like and made up into aqueous alcoholic solutions from which further concentrations of vitamins can be extracted by means of appropriate selective solvents such as petroleum hydrocarbons. It is also permissible to distill off concentrations of vitamins from the extracted oil by so-called molecular distillation in which the extracted oil is subjected to distillation under very low vacuum and in proximity to a cold surface in such manner that the vitamins distilled without actual boiling of the oil. These methods of concentration are outlined in the textbook, *Chemistry and Physiology of the Vitamins* by H. R. Rosenberg.

An advantage of preliminarily extracting the vitamin A bearing oils with polar solvents in accordance with the provisions of the present invention before subjecting them to chemical treatment or to molecular distillation resides in the fact that it is possible greatly thus to reduce the proportion of oil requiring such drastic treatment as involved in the chemical separation of vitamins or the molecular distillation. The overall expenses of the operation are thus reduced to a substantial degree. Moreover, there is less decomposition of vitamins by reason of the drastic treatment. The raffinate fractions are excellently adapted for food purposes such as stock feeds, or even for human consumption where a source of vitamins of low concentration is desired.

It will be apparent to those skilled in the art that the forms of the invention herein illustrated are merely by way of examples and that numerous modifications may be made therein without departure from the spirit of the invention or the scope of the appended claims.

We claim:

1. A process of obtaining a concentrate of vitamin A from fish liver oil containing said vitamin which process comprises passing the oil upwardly in countercurrent flow through a vertically elongated zone of downwardly flowing organic polar solvent which is partially miscible therewith, the oil-solvent mixture in the upper portion of the zone being maintained at a substantially higher temperature than the solvent containing dissolved oil in the lower portion of

the zone whereby to obtain a cool extract of glyceride oil and solvent which is highly enriched in vitamin A and a warm raffinate which is correspondingly impoverished in vitamin A, drawing off the raffinate at the top of the zone and the solution of solvent and extract at the bottom of the zone and evaporating the solvent to obtain the concentrate.

2. A process as defined in claim 1 in which the solvent is furfural.

3. In a process of separating a concentrate of vitamin A from a fish liver oil containing said vitamin, the steps of continuously flowing one volume of said oil upwardly and flowing three to thirty volumes of organic polar solvent, which is but partially miscible with the oil, downwardly through a vertically elongated zone, the temperature in the zone being within a range of 10 to 80° C. and being sufficient to effect solution of 20 to 75% of the feed oil as an extract in the solvent, collecting a liquid raffinate phase of oil impoverished in vitamin A at a point above that of introduction of solvent, continuously withdrawing the raffinate, collecting the liquid extract of oil in solvent, continuously drawing off as an extract phase at a point below that of introduction of the oil, evaporating solvent from the extract phase, passing the oil from said phase upwardly in countercurrent flow through a second vertically elongated zone of downwardly flowing partially miscible solvent, the zone being maintained at a temperature to obtain a second extract solution of oil in solvent and a second raffinate of oil containing some solvent, collecting the second extract solution at the bottom of the zone, drawing off said solution, evaporating off the solvent to obtain the desired concentrate of vitamin A and recycling the second raffinate phase by admixing it with the feed oil to the first extraction zone.

4. A process as defined in claim 3 in which the solvent is furfural.

5. A process as defined in claim 3 in which the solvent is furfural, the second zone being operated at a substantially lower temperature than the first.

6. In a process of obtaining a concentrate of vitamin A from a fish liver oil containing said vitamin, the steps comprising flowing one volume of the oil upwardly in intimate contact with three to thirty volumes of downwardly flowing organic polar solvent which is but partially miscible with the oil at temperatures of 10 to 80° C., the zone being at a temperature adapted to obtain a liquid extract solution of 25 to 75% of the oil in the solvent, drawing off the liquid extract solution of oil and solvent at the bottom of the zone, evaporating the solvent from the extract solution, then further intimately countercurrently contacting the extracted oil with polar solvent in a second elongated zone to obtain an overall extraction of about 15% of the oil, then evaporating the solvent from the resultant liquid extract phase to obtain an extract product which is greatly enriched in vitamin A as compared with the original oil.

7. A process of obtaining a concentrate of vitamin A from fish liver oil which process comprises flowing one volume of the oil upwardly through three to thirty volumes of downwardly flowing organic polar solvent which is but partially miscible with the oil at temperatures of 10 to 80° C., in a vertically elongated zone at a temperature to obtain an extract yield of 2 to 25% of the original oil, continuously drawing off a

liquid raffinate of oil impoverished in vitamin A at the top of the zone and an extract solution of solvent and 2 to 25% of the original oil at the bottom of the zone, the concentration of vitamin A in the oil of the extract solution being at least twice as great as the original oil, evaporating the solvent from the extract solution and returning 10 to 90% thereof to said zone at a point below that of introduction of the feed oil and above the point of withdrawal of the extract solution.

8. A process as defined in claim 7 in which the solvent is furfural.

9. A continuous process for preparing a vitamin A concentrate from a charge oil which is a fish liver oil containing vitamin A, by fractionation with furfural at a temperature within a range of 10 to 80° C., said process being carried out in a vertically extended fractionation zone having a furfural inlet and a raffinate phase outlet near the upper end, an extract phase outlet near the lower end and a charge oil inlet in the intermediate portion of said zone, which process includes the steps of: continuously introducing said charge oil and said furfural into a vertically extended fractionation zone having a furfural inlet and a raffinate phase outlet near the upper end, an extract phase outlet near the lower end and a charge oil inlet in the intermediate portion of said zone; separately withdrawing extract and raffinate phases from said extract phase outlet and said raffinate phase outlet respectively, said extract phase constituting about 2 to 25% of the original feed oil and having a temperature in the range of 10 to 80° C., separating furfural from at least a part of said extract phase to produce a reflux liquid having substantially lower density than said extract phase, and flowing said

reflux liquid upwardly in said fractionation zone to contact and rectify said downwardly flowing extract phase; maintaining the rate of flow of said reflux liquid to produce at some point within the fractionation zone a reflux flow rate in the range of 10 to 90% of the rate at which extract oil is withdrawn from said fractionation zone; maintaining furfural introduction at said furfural inlet at a rate in a range of 3 to 30 volumes of furfural to one volume of charge oil; and recovering a vitamin concentrate product from said extract phase.
